UNITED STATES PATENT OFFICE.

PATRICK F. FOLEY, OF NEW YORK, N. Y.

OPERATING DEVICE FOR ELEVATOR-CARS.

SPECIFICATION forming part of Letters Patent No. 742,623, dated October 27, 1903.

Application filed June 23, 1903. Serial No. 162,745. (No model.)

To all whom it may concern:

Be it known that I, PATRICK F. FOLEY, a citizen of the United States, and a resident of the city of New York, borough of Manhattan, in the county and State of New York, have invented a new and Improved Operating Device for Elevator-Cars, of which the following is a full, clear, and exact description.

This invention relates to elevators; and it consists substantially in the construction, organization, and combinations of parts hereinafter particularly described and claimed.

The invention has reference more especially to devices for raising and lowering the cars of elevators; and one of the principal objects of my invention is to provide means for overcoming numerous disadvantages and objections found to exist with many other devices hitherto devised for similar purposes and also to provide devices of this kind which are exceedingly simple as well as comparatively inexpensive to manufacture and comprising few elements or parts, which are not easily broken or dislocated nor liable to get out of order.

A further object of my invention is to provide devices of the character referred to which are effective and reliable in use or operation, as well as easily controlled and regulated, and which also possess the capacity for long and repeated service.

The above and additional objects are attained by means substantially such as are illustrated in the accompanying drawings, in which similar characters of reference indicate corresponding parts in both the figures.

Figure 1 represents an embodiment of my improvements in vertical side elevation; and Fig. 2 is a perspective view representing more clearly the embodiment of the plural operating-cables employed and the disposition of the different double guides or sheaves therefor.

Before proceeding with a more detailed description it may be stated that in the form of my improvements herein shown I employ suitable guides for preferably two vertically movable frames which are caused to simultaneously rise and fall for the purpose of effecting the lowering and raising of the car or cage of the elevator, said frames supporting thereon suitable guides or sheaves for one or more endless cables through the medium of

which the frames are operated directly from a suitable motor. The car or cage of the elevator is connected with one of the movable frames by means of an independent cable, this latter, as well as the endless operating cable or cables referred to, working over suitable stationary guides or sheaves therefor, as will presently appear, and while I have herein represented my improvements in a certain preferred form it is apparent, of course, that I am not limited to the precise details thereof in practice, since immaterial changes may be made therein coming within the scope of my invention. The said rising and falling frames may each be counterweighed relatively to the other, as well as to the cage or car, and in the use of more than a single endless operating-cable for said frames and car I preferably employ for each additional cable an independent adjusting device for taking up slack produced therein from any cause, the first cable being kept taut by the weight of one of the frames, but which cannot be readily effected for a plurality of cables on account of unequal stretching thereof, all as will be apparent.

Specific reference being had to the accompanying drawings by the designating characters marked thereon, 1 1 and 2 2 represent duplicate sets of vertical guides or rails which are suitably supported in position with those of each set properly spaced apart, and located at the upper ends of said guides or rails, preferably one above the other, are the horizontal beams or timbers 3 and 4, which may be supported in any suitable manner. Working vertically between the guides or rails 1 1 is a slidable frame 5, constructed, preferably, of upper and lower horizontal members 6 and 7, (each preferably in duplicate, though but one of each is shown,) which are connected vertically by rods 8, upon which may be placed any desired number of counterweights 9 for the elevator car or cage 10, to be presently again referred to, it being noted that the sides of said frame at 11 are adapted to fit the said guides or rails 1 1. Similarly working between the guides or rails 2 2 is another vertically-slidable frame 12, likewise preferably constructed of upper and lower horizontal members 13 and 14, (each also being preferably in duplicate, though but one of each is

shown,) which are connected vertically by rods 15, upon which may also be placed any desired number of counterweights 16 for establishing proper balance of this frame with the frame first named, as well as with the said car or cage 10.

- Preferably located between the guides or rails 11, at the base thereof, is an ordinary electric or other suitable motor 17, to one end 10 of the main operating-shaft 18 of which are fitted (in the present instance) two sets of duplicate differential sheaves or pulleys 19 and 20, and fitted to the said slidable frame 5 at 21 is a double guide sheave or pulley 22. 15 Also fitted to the slidable frame 12 at 23 is a single guide sheave or pulley 24, and likewise fitted at 25, between the arms of a yoke 26, is also a single guide sheave or pulley 27, said yoke having a threaded shank or stem 28 20 working through a suitable part of the frame 12, as shown, and provided with nuts 29 and 30, by which the yoke may be adjusted and secured at different positions vertically. The beam or timber 3 has mounted thereon the 25 double stationary guide sheaves or pulleys 31, 32, and 33, (see Fig. 2,) while the said beam or timber 4 has similarly mounted thereon the single stationary guide sheaves or pulleys 34 and 35, as shown. Passing over the severally- 30 mentioned double guide sheaves or pulleys are preferably duplicate operating cables or cords 36, by which the elevator-cage is caused to be raised and lowered, as presently explained, and in order that the directions of 35 said cables or cords may be readily understood the same may better be traced by starting from a given point. Thus starting from x in Figs. 1 and 2 and proceeding downwardly it will be seen that the said duplicate cables 40 or cords first pass beneath and around the double sheave 19, thence upwardly and over the double stationary sheave 32, thence downwardly and beneath the separate sheaves 24 and 27 on the frame 12, thence upwardly 45 again and over the double stationary sheave 33, thence across and over the double stationary sheave 31, thence downwardly and beneath the double sheave 20, and finally upwardly and over the double sheave 22 and 50 downwardly again to x .
- Connected to the upper part of the frame 5 at 37 is one end of an independent preferably single cable 38, which passes upwardly and over the single guide-sheaves 34 and 35, 55 and thence downwardly and has its other end connected at 39 to the upper part of the car or cage 10. (See Fig. 1.)
- Assuming the motion of the motor-shaft to be in the direction indicated by the curved 60 arrow in Fig. 1, it will be seen that the two frames will be operated (through the medium of said double cables) in an upward direction, thereby causing the car or cage to descend, and that on reversing the direction of motion of said motor-shaft the said frames and car will also be operated reversely to that just described, it being understood, of course, that

any desired form of starting and stopping devices may be employed, as well as any suitable means for regulating or controlling the 70 motor, which latter may be of any approved form. It will also be seen that one of the duplicate operating cables or cords 36 will be maintained in a taut condition by the weight of the frame 12, while the other one 75 of said cables or cords may always be kept in similar condition by proper adjustment of the guide-sheave 27, as already explained.

I may employ but a single continuous operating cable or cord for the two frames, as 80 already mentioned, in which case one of each of the duplicate differential guide-sheaves herein described will be dispensed with. On the other hand, I may employ any desired number of such cables or cords, in which event 85 the number of said guide-sheaves will be correspondingly increased, as will be understood. Preferably, however, I employ duplicate operating cables or cords, with an equal number of differential guide-sheaves therefor, together with an adjusting device for one 90 of them, as shown.

Having thus described my invention, I claim as new and desire to secure by Letters Patent—

1. In elevators, the combination with a car, and a suspensory cable therefor, of plural vertically-movable frames, each carrying a guide-sheave, and to one of which frames said suspensory cable is connected, a motor having 10 a shaft provided with a set of differential guide-sheaves, and an endless operating-cable for the car, passing from beneath the larger sheave on said shaft, to and over a stationary guide, thence to and beneath the sheave 105 on one of the frames, to and over other stationary guides, thence to and beneath the smaller sheave on the shaft, and finally to and over the sheave on the other frame, and back to beneath the said larger sheave. 110

2. In elevators, the combination with a car, and a suspensory cable therefor, of plural vertically-movable frames, each carrying a guide-sheave, and provided with counterweights, and to one of which frames said suspensory 115 cable is connected, a motor having a shaft provided with a set of differential guide-sheaves, and an endless operating-cable for the car, passing from beneath the larger sheave on said shaft, to and over a stationary guide, thence to and beneath the sheave on one of the frames, to and over other stationary guides, thence to 120 and beneath the smaller sheave on the shaft, and finally to and over the sheave on the other frame, and back to beneath the said larger sheave. 125

3. In elevators, the combination with a car, and a suspensory cable therefor, of plural vertically-movable frames, each carrying plural guide-sheaves, and to one of which frames said suspensory cable is connected, a motor having 130 a shaft provided with plural sets of differential guide-sheaves, and endless operating-cables for the car, passing from beneath the

larger sheaves on the shaft, to and over plural stationary guides, thence to and beneath the sheaves on one of the frames, to and over other plural stationary guides, thence to and beneath the smaller sheaves on the shaft, and finally to and over the plural sheaves on the other frame, and back to beneath the said larger plural sheaves.

4. In elevators, the combination with a car, and a suspensory cable therefor, of plural vertically-movable frames, each carrying plural guide-sheaves, and to one of which frames said suspensory cable is connected, a motor having a shaft provided with plural sets of differential guide-sheaves, and endless operating-cables for the car, passing from beneath the larger sheaves on the shaft, to and over plural stationary guides, thence to and beneath the sheaves on one of the frames, to and over other plural stationary guides, thence to and beneath the smaller sheaves on the shaft, and finally to and over the plural sheaves on the other frame, and back to beneath the said larger plural sheaves, said frames each being provided with counterweights.

5. In elevators, the combination with a car, and a suspensory cable therefor, of plural vertically-movable frames one carrying a double guide-sheave and the other two single guide-sheaves, and to one of which frames said suspensory cable is connected, a motor having a shaft provided with duplicate sets of differential guide-sheaves, and endless operating-cables for the car, passing from beneath the larger sheaves on the shaft, to and over duplicate stationary guides, thence to and beneath the single sheaves on one of the frames, to and over other duplicate stationary guides, thence to and beneath the smaller sheaves on the shaft, and finally to and over the double sheaves on the other frame, and back to beneath the said larger duplicate sheaves.

6. In elevators, the combination with a car, and a suspensory cable therefor, of plural vertically-movable frames one carrying a double guide-sheave and the other two single guide-sheaves, and to one of which frames said suspensory cable is connected, a motor having a shaft provided with duplicate sets of differential guide-sheaves, and endless operating-cables for the car, passing from beneath the larger sheaves on the shaft, to and over duplicate stationary guides, thence to and be-

neath the single sheaves on one of the frames, to and over other duplicate stationary guides, thence to and beneath the smaller sheaves on the shaft, and finally to and over the double sheaves on the other frame, and back to beneath the said larger duplicate sheaves, said frames each being provided with counterweights.

7. In elevators, the combination with a car, and a suspensory cable therefor, of plural vertically-movable frames, each carrying duplicate guide-sheaves, and to one of which frames said suspensory cable is connected, a motor having a shaft provided with duplicate sets of differential guide-sheaves, endless operating-cables for the car, passing from beneath the larger sheaves on the shaft, to and over duplicate stationary guides, thence to and beneath the sheaves on one of the frames, to and over other duplicate stationary guides, thence to and beneath the smaller sheaves on the shaft, and finally to and over the duplicate sheaves on the other frame, and back to beneath the said larger duplicate sheaves, and means on one of said frames for adjusting one of the said sheaves.

8. In elevators, the combination with a car, and a suspensory cable therefor, of plural vertically-movable frames each carrying duplicate guide-sheaves, and to one of which frames said suspensory cable is connected, a motor having a shaft provided with duplicate sets of differential guide-sheaves, endless operating-cables for the car, passing from beneath the larger sheaves on the shaft, to and over duplicate stationary guides, thence to and beneath the sheaves on one of the frames, to and over other duplicate stationary guides, thence to and beneath the smaller sheaves on the shaft, and finally to and over the duplicate sheaves on the other frame, and back to beneath the said larger duplicate sheaves, and a yoke for adjustably supporting one of the sheaves on one of the frames, said yoke having a threaded stem and operating and fastening nuts thereon.

In testimony whereof I have signed my name to this specification in the presence of two subscribing witnesses.
